UNITED STATES PATENT OFFICE.

ROY B. WILTSIE, OF SAN DIEGO, CALIFORNIA.

AIR HEATER.

Application filed January 22, 1925. Serial No. 4,056.

My invention relates to heaters, particularly adapted for heating air for dwellings and other buildings, and the objects of my invention are: first, to provide a heater whereby a relatively large volume of air may be heated to a moderate temperature instead of a relatively small volume of air being heated to a high temperature, as in heaters now in use; second, to provide a heater of this class having a heating core through which the hot gases of combustion are adapted to circulate in an upward and outward direction from the source of heat positioned at the lower portion of the same and around and against substantially all sides of which air is adapted to circulate for heating the air; third, to provide a heater of this class having a middle heating core through which hot gases of combustion are adapted to circulate for heating the walls of the same, and also having an inner and outer air heating chamber, the inner chamber being adapted to heat air to a relatively high temperature and the air in the outer chamber being adapted to cool the outer wall of the inner chamber, thereby slightly heating the air in the outer chamber, the air in the outer chamber being combined in relatively large quantities with the hot air of the inner chamber; fourth, to provide a heater of this class having a core through which heated gases of combustion are adapted to circulate, and which is provided with a plurality of angular staggered baffles inclined upwardly toward the rear end, forming a substantially upwardly zigzag and backwardly inclined channel for the passage of hot gases of combustion therethrough, thereby providing a great and efficient heating surface for air adapted to circulate around and against the heated walls thereof; fifth, to provide a core for a heater of this class which is provided with a small burner at the lower ends of the inclined passages thereof; sixth, to provide a core for a heater of this class having a pair of upwardly zigzag and upwardly and backwardly inclined passages, the passage of the hot gases of combustion through either being separately controlled to provide greater or less heat at one side of the heater than at the other; seventh, to provide a core for a heater of this class having a pair of wide upwardly zigzag channels, separated a greater distance from each other at their upper than at their lower ends, and also at their upwardly inclined ends than at their lower ends; eighth, to provide as a whole a novelly constructed heater of this class, and ninth, to provide a hot air heater which is simple and economical of construction, durable, efficient, easy to control, and which will not readily deteriorate or get out of order.

With these and other objects in view, as will appear hereinafter, my invention consists of certain novel features of construction, combination and arrangement of parts and portions, as will be hereinafter described in detail and particularly set forth in the appended claims, reference being had to the accompanying drawings and to the characters of reference thereon, which form a part of this application, in which:

Figure 1 is a longitudinal sectional elevational view of my heater, taken through 1—1 of Fig. 2, showing certain parts and portions in elevation to facilitate the illustration, and showing the movable heat diverting member in a certain shifted position by dotted lines; Fig. 2 is a partial front elevational and partial sectional view thereof, with the section taken through 2—2 of Fig. 1; Fig. 3 is a top view thereof, with portions of the walls of the outer and inner chambers partially broken away and in section to facilitate the illustration; Fig. 4 is a fragmentary sectional view of my heater, taken through 4—4 of Fig. 1; Fig. 5 is an enlarged front elevational view of the core of my heater in a slightly modified form of construction, with certain parts and portions thereof broken away and in section to facilitate the illustration, and Fig. 6 is a side elevational view thereof.

Like characters of reference refer to similar parts and portions throughout the several views of the drawings.

The heating core 1, heat diverting plate 2, burner 3, inner casing 4, outer casing 5, brackets 6 and 7, legs 8, fresh air pipes 9 and 10, flues 11, dampers 12, hot air pipes 13, 14 and 15, heat deflector 16, heat deflector operating rod 17, and the drainpipe 18, constitute the principal parts and portions of my heater.

The bottom portion of the core 1 is provided with a firebox 1^a, at the one end of which, preferably the front end, is positioned a burner 3 of any suitable construction. At the upper portion of this firebox is supported a heat diverting plate 2 which

extends from the one end of the core in which the burner is positioned to the opposite end thereof, its side edges being spaced from the side walls of the core, as shown best in Figs. 2 and 4. The side edges of the plate 2 are preferably turned upwardly, so as to facilitate the flow of gases of combustion to the compartment at the upper side of the plate, and also to retain condensed water vapor dripping from the upper portion of the core. Said plate is also provided with a pair of downwardly projecting portions extending longitudinally therewith at its lower side to facilitate the conduction of the heat from the burner to the opposite end of the core. The grooves 2^a at the upper side of the plate, forming the projections on the lower side thereof, provide channels for the conduction of condensed water vapor to the lower front end of the plate from which the same is conducted by means of a drainpipe 18.

The upper portion of the core is divided into two separate sections A and B, each of which consists of an angular zigzag channel extending upwardly substantially from the plate 2 and discharging into enlarged chambers 1^b at the upper ends of the sections A and B of the core 1. These channels 1^c, which zigzag upwardly, are also inclined upwardly from the end of the core in which the burner is positioned, or as specifically illustrated in the drawings, inclined upwardly toward the rear end of the core. To the front ends of the enlarged chambers 1^b at the upper ends of the separate sections A and B of the core 1 are respectively connected flues 11, which are provided with dampers 12, said dampers being adapted to regulate the heat in each section of the core. The flues 11 are connected to the core, as stated, so that all remote portions of the core may be heated as efficiently as possible.

It will be seen from the above that the hot gases of combustion from the burner 3 will pass around the side edges of the plate 2 and also along the longitudinal channel at the under side thereof toward the opposite end of the core, then pass into the upwardly and angularly zigzag passages 1^c into the chambers 1^b and out of the flues 11. The hot gases of combustion, passing into the front end of the core and impinging against the angular baffle walls forming the channel, heat the same and tend, by reason of the upward inclination of these zigzag channels or baffle walls toward the rear end of the core, to deflect said gases toward the rear end of the same, thus substantially heating all walls of the core.

The front end of the core 1 is preferably raised above the floor level to permit ample supply of air to support combustion of the burner.

Around the core 1 is positioned an inner

shell or casing 4, which is preferably spaced from the floor level and supported relatively to the core 1 by means of brackets 6, as shown best in Figs. 1 and 3. The front wall of the inner shell or casing 4 is partially removed, as shown best in Figs. 2 and 3, providing an opening for the conduction of air thereto from the fresh air pipe 9 secured to the front end and lower portion of the outer shell or casing 5 positioned around the inner casing 4. The rear wall of the inner shell or casing 4 is inclined upwardly and backwardly so that the space at the upper portion of the rear end of the inner shell or casing 4 from the wall of the outer shell or casing 5 is considerably less than at their lower ends, so that air admitted, by means of the air pipe 10 at the lower portion of the rear end of the outer casing 5, is forced, by the nature of the construction, in the spaces between the side walls of the inner and outer shells or casings. Said inner and outer shells or casings are supported relatively to each other by means of brackets 7, as shown in Figs. 1 and 3. The outer shell or casing 5 is also preferably spaced from the floor level and supported on the legs 8. In the upper wall of the inner casing 4 is provided a plurality of outlets 4^a, 4^b and 4^c for permitting the discharge of the heated air within the casing 4 into the upper portion of the outer casing 5. At the upper end of the outer casing 5 are also provided outlet openings which communicate with hot air conductors 13, 14 and 15 which are preferably so positioned as to register substantially with the openings 4^a, 4^b and 4^c of the inner casing 4.

The core 1 is so constructed that the space between the sections A and B thereof increases upwardly and backwardly so as to provide for the expansion of the heated gases, the taking in of more air and the deflection of the heated air over the whole of the heated walls of the core 1.

The inner shell or casing 4 is provided at the lower portions of its side walls with outwardly bent deflecting portions 4^d to facilitate the discharge of more air into the interior of the inner casing from the lower end of the outer casing.

It will be readily seen that, by reason of this construction, as stated, most of the heated air is directed toward the rear end of the inner casing 4. To obviate the discharge of most of the hot air through the opening 4^c and into the hot air pipe 15, I have provided an air deflector 16 at the upper rear portion of the inner casing 4, which deflector is pivotally mounted on said inner casing and is adapted, when in a lower position, as shown by solid lines in Fig. 1 of the drawings, to prevent discharge of hot air through the opening 4^c, and when in a slightly raised position, to divert the hot air

toward the other hot air pipes 13 and 14. To this deflector 16 is connected a rod or other suitable means 17 for regulating the discharge of air through the opening 4.

5 In the modified form of construction of the core of my heater, as shown in Figs. 5 and 6 of the drawings, the lower few of the zigzag channel portions 1^a are preferably slightly enlarged in thickness. Extending 10 transversely through portions of these enlarged portions of the zigzag channels of the core are ports 1^a which serve to conduct air from the outer sides of the core to the space between the separate sections thereof, and 15 also to heat said air in the passage through said ports. The two sets of the ports 1^a in each section A and B of the core are preferably staggered relatively to each other, as shown best in Fig. 6. The space between 20 the separate sections A and B of the core in the modified form of construction is also preferably considerably larger than in the preferred construction to take care of the additional air discharged into said space 25 through the ports 1^a.

It is obvious from this construction, as illustrated in the drawings and disclosed in the foregoing specification, that I have provided a heater particularly adapted for heating 30 large volumes of air to a moderate temperature, as aimed at and set forth in the objects of the invention, and though I have shown and described a particular construction, combination and arrangement of 35 parts and portions and a certain modification thereof, I do not wish to be limited to this particular construction, combination and arrangement nor to the modification, but desire to include in the scope of my invention the construction, combination and arrangement substantially as set forth in the appended claims.

Having thus described my invention, what I claim as new and desire to secure by Letters Patent is:

1. In a heater of the character described, a heating core adapted to permit the flow and confine the passage of gases of combustion within the core and from the lower 50 to the upper end thereof, a burner positioned at the lower portion of said core, an inner casing positioned around and spaced from said core, and an outer casing positioned around and spaced from said inner casing adapted to permit the passage of air around all sides of said inner casing for cooling the latter and for heating the air in the space between said casings.

2. In a heater of the character described, 60 a heating core adapted to permit the passage of gases of combustion from the lower to the upper end thereof, a burner positioned at the lower portion of said core, an inner casing positioned around and spaced from said core, an outer casing positioned around

and spaced from said inner casing adapted to permit the passage of air around all sides of said inner casing for cooling the latter and for heating the air in the space between said casings, air inlet conductors communicating 70 with the lower portions of the front and rear ends of said outer casing, and hot air discharge pipes communicating with the upper end of said outer casing.

3. In a heater of the character described, 75 a heating core adapted to permit the passage of gases of combustion from the lower to the upper end thereof, a burner positioned at the lower portion of said core, an inner casing positioned around and spaced from 80 said core, an outer casing positioned around and spaced from said inner casing adapted to permit the passage of air around all sides of said inner casing for cooling the latter and for heating the air in the space between 85 said casings, air inlet conductors communicating with the lower portions of the front and rear ends of said outer casing, and hot air discharge pipes communicating with the upper end of said outer casing, said inner 90 casing being provided at its upper end with openings adapted to discharge air heated therein by said core into the upper portion of said outer casing.

4. In a heater of the character described, 95 a heating core provided at its lower portion with a firebox and at its upper portion with a double-walled air heating element having an angular zigzag passage extending from the lower to the upper end thereof and secured to and communicating at its lower end with said firebox, the portions of said heating element forming said zigzag channel being inclined upwardly from the one end thereof to the other, and a burner positioned 100 in said firebox at the one end thereof only at which the lower portions of the inclined 105 portions forming the zigzag channel terminate with the one end wall of the core.

5. In a heater of the character described, 110 a heating core provided at its lower portion with a firebox and at its upper portion with angular zigzag passages extending from the lower to the upper end thereof, the portions of said core forming said zigzag channel being inclined upwardly from the one end thereof to the other, a burner positioned in said firebox at the one end thereof at which the lower portions of the inclined 115 portions forming the zigzag channel terminate with the one end wall of the core, and a heat diverting plate positioned between said burner and the zigzag channel portion of said core for diverting the heated gases from said burner to the sides of the core and to the 120 opposite end thereof from said burner.

6. In a heater of the character described, 125 a heating core provided at its lower portion with a firebox and at its upper portion with spaced apart angular zigzag passages with 130

- individual flues, said passages extending from the lower to the upper end thereof, the portions of said core forming said zigzag passages being inclined upwardly from the one end thereof to the other, and a casing positioned around and spaced from said core on all sides thereof and provided at its upper end with openings adapted to discharge heated air therefrom and also open at its one end.
- 10 7. In a heater of the character described, a heating core provided at its lower portion with a firebox and at its upper portion with angular zigzag passages extending from the lower to the upper end thereof, the portions of said core forming said zigzag channel being inclined upwardly from the one end thereof to the other, an inner casing positioned around and spaced from said core on all sides thereof and provided 15 at its upper end with openings adapted to discharge heated air therefrom and also open at its one end, and an outer casing positioned around and spaced at its sides and upper end from said inner casing and provided at its upper end with hot air discharge pipes and at the ends of its lower portion with air inlet pipes adapted to discharge fresh air into the space between said inner and outer casings and to said core.
- 20 8. In a heater of the character described, a heating core provided at its lower portion with a firebox and at its upper portion with angular zigzag passages extending from the lower to the upper end thereof, the portions 25 of said core forming said zigzag channel being inclined upwardly from the one end thereof to the other, an inner casing positioned around and spaced from said core on all sides thereof and provided at its upper end with openings adapted to discharge heated air therefrom and also open at its one end, an outer casing positioned around and spaced at its sides and upper end from said inner casing and provided at its upper 30 end with hot air discharge pipes and at the ends of its lower portion with air inlet pipes adapted to discharge fresh air into the space between said inner and outer casings and to said core, and a heat deflecting member 35 shiftably mounted at the upper end of said inner casing and adapted to divert the air heated therein and discharged from one of the openings at the upper end thereof.
- 40 9. In a heater of the character described, a core provided at its lower end with a firebox merging into a pair of separate spaced apart upright air heating sections provided with angular zigzag passages forming angular baffle means for the passage of the heated gases from said firebox to the upper ends of said zigzag channel sections, said baffle means being inclined upwardly from the front to the rear end thereof.
- 45 10. In a heater of the character described, a core provided at its lower end with a firebox merging into a pair of separate spaced apart upright air heating sections provided with angular zigzag passages forming angular baffle means for the passage of the heated gases from said firebox to the upper ends of said zigzag channel sections, said baffle means being inclined upwardly from the front to the rear end thereof, the space between said upright zigzag channel sections increasing from the lower to the upper end, and also from the front to the rear end thereof.
- 50 11. In a heater of the character described, a core provided at its lower end with a firebox merging into a pair of separate spaced apart upright air heating sections provided with angular zigzag passages forming angular baffle means for the passage of the heated gases from said firebox to the upper ends of said zigzag channel sections, said baffle means being inclined upwardly from the front to the rear end thereof, the space between said upright zigzag channel sections increasing from the lower to the upper end, and also from the front to the rear end thereof.
- 55 12. In a heater of the character described, a core provided at its lower end with a firebox merging into a pair of separate spaced apart upright air heating sections provided with angular zigzag passages forming angular baffle means for the passage of the heated gases from said firebox to the upper ends of said zigzag channel sections, said baffle means being inclined upwardly from the front to the rear end thereof, the space between said upright zigzag channel sections increasing from the lower to the upper end, and also from the front to the rear end thereof, said channel sections being provided at their upper ends with enlarged chambers, discharge conductors communicating with the normally lower inclined ends of said chambers, and a heat diverting plate positioned in said firebox and spaced from the side edges thereof adapted to divert the heat to the sides of the core and from one end thereof to the other.
- 60 13. In a heater of the character described, a core provided at its lower end with a firebox merging into a pair of spaced apart upright air heating sections provided with angular zigzag channels forming angular baffle means for the passage of the heated gases from said firebox to the upper ends of said zigzag channel sections, said baffle means being inclined upwardly from the front to the rear end thereof, the space between said upright zigzag channel sections increasing from the lower to the upper end, and also from the front to the rear end thereof, said

channel sections being provided at their upper ends with enlarged chambers, discharge conductors communicating with the normally lower inclined ends of said chambers, a 5 heat diverting plate positioned in said firebox and spaced from the side edges thereof adapted to divert the heat to the sides of the core and from one end thereof to the other, an inner casing surrounding said core 10 and spaced at its sides and upper end therefrom and provided at its upper end with discharge openings, and an outer casing positioned around and spaced from said inner casing and provided at its upper end with 15 discharge openings and at its lower end with air inlet openings.

14. In a heater of the character described, a heating core comprising a firebox, and a double-walled air heating element secured to 20 and communicating therewith at its one end, heat diverting means separating said heating element and firebox, said heating element having a zigzag passage therethrough formed of angularly positioned and staggered channel portions 25 therein.

15. In a heater of the character described, a heating core comprising a firebox, and a double-walled air heating element communicating therewith at its one end, heat diverting 30 means separating said heating element

and firebox, said heating element having a zigzag passage therethrough formed of angularly positioned and staggered channel portions therein, the whole exterior angular surfaces of said heating element being 35 adapted to be subjected to circulating air.

16. In an air heater, a heating core comprising a relatively large combustion chamber, and a relatively thin, double-walled air heating element connected to and communicating therewith at its one end and formed of angularly positioned and staggered channel portions forming with one another an extended zigzag passage therethrough. 40

17. In an air heater, a heating core comprising a relatively large combustion chamber, and a relatively thin, double-walled air heating element communicating therewith at its one end and formed of angularly positioned and staggered channel portions 50 forming with one another an extended zigzag passage therethrough, the whole exterior angular surfaces of the angularly and staggered channel portions of said heating element being adapted to be subjected to air 55 for heating the latter. 45

In testimony whereof, I have hereunto set my hand at San Diego, California, this 16th day of January, 1925.

ROY B. WILTSIE.
